ATTORNEY

UNITED STATES PATENT OFFICE.

EDWARD THOMAS OSBORN, OF SEATTLE, WASHINGTON.

BATH APPLIANCE.

Application filed May 21, 1924. Serial No. 714,767.

To all whom it may concern:

Be it known that I, EDWARD THOMAS OSBORN, a subject of Great Britain, residing at Seattle, in the county of King and State of Washington, have invented certain new and useful Improvements in Bath Appliances, of which the following is a specification.

This invention relates broadly to cabinet 10 bath devices of the character disclosed in U. S. Patent No. 1,329,994 issued to me February 3, 1920.

The primary object of the invention is to simplify and otherwise improve the construction and efficiency of devices of the character above referred to.

A further object is to provide foot and shower bath apparatus associated with a temporarily formed cabinet that does not 20 permanently occupy any room space and is peculiarly applicable for use in a living room of an apartment house, hotel, or the like, where permanent space cannot advantageously be allotted to such conveniences.

With these and other objects in view, the invention resides in the novel features of construction, arrangement and combination of parts hereinafter described and claimed.

In the accompanying drawing,—

Figure 1 is a view in horizontal section of devices embodying my invention, the grid being partly broken away to disclose the drainage sump and portions of the gutter. Fig. 2 is a similar view taken at a higher 35 elevation than Fig. 1, the movable walls of the cabinet being represented in their operative positions, and with the foot bath cover shown in place. Fig. 3 is a vertical section taken substantially on line 3—3 of Fig. 2. Fig. 4 is a fragmentary detail sectional view to an enlarged scale on line 3—3 of Fig. 2. Fig. 5 is a detail sectional view on line 5—5 of Fig. 4.

In said drawing, the reference numerals 40 10 and 11 represent a side wall and an end wall, respectively, of a living room.

In the corner of said room and adjacent to said walls is a vessel or sink 12, constituting a foot-bath tub, of rectangular shape, 50 preferably, which is disposed to have its upper edge flush or in a plane with the floor level 13 of the room.

The sink 12 is surrounded by a series of gutters 14 of less depth than the sink and 55 arranged to drain into a well or sump 15 having an outlet into a waste pipe 16 which

includes a trap element 17. 18 represents an opening provided in the partition between the sump 15 and the interior of the sink to serve as a drainage outlet for the latter. 19 represents a plug stopper engageable in said outlet for use when the sink is to be employed as a foot bath tub. The sink, gutter and sump above mentioned is desirably provided by a single body constructed of a material such, for example, as porcelain, or other known suitable waterproof compositions.

20 represents a frame positioned upon said body and affording an abutment for 70 the room floor boards, as shown in Figs. 3 and 4, the upper surface 21 of which is in a plane with the upper surface 22 of the sink walls and also with respect to the floor surface 13 of the room.

Seated in a rabbet 24 of the sink walls is a removable cover 26 which is preferably provided with drain apertures 25 extending from grooves 27 as shown in Figs. 2 and 3.

Seated in rabbets 28 above the gutters 14 80 is a grille 29 comprising spaced bar elements 30 and 31 disposed longitudinally and at right angles, respectively, with regard to the respective gutter members. The longitudinal bars 30 have their upper surfaces in a plane with the floor and the transverse bars 31 (Figs. 4 and 5) are arranged, preferably, to have their upper beveled surfaces disposed somewhat below the top surface of the bars 30 so that water meets the 90 maximum hindrance getting under the doors to reach the room floor 13.

32 represents a pipe for supplying water for a foot bath into the sink, said pipe leading from a service pipe 33 (Fig. 3) and is 95 provided with a shut-off or regulating valve, indicated by 34. A second pipe 35 extends upwardly from said service pipe and is provided with a sprinkler nozzle 36 for use as a shower bath subject to the regulation of a valve 37.

Associated with the devices above described are movable wall members 38 and 39 in the nature of doors which are hingedly connected at 40 and 41 to the respective room walls 10 and 11 or, as shown, to casing strips 42 and 43 which are rigid with the room walls. The doors thus arranged are adapted to be housed, see Fig. 1, in proximity with the respective walls 10 and 11 105 and within recesses 44 and 45 provided by said casing strips; or the doors may be

swung outwardly from said walls into the position in which represented in Figs. 2 and 3 to furnish with the room walls 10 and 11 an enclosure for a person using the shower or foot bath. The door 38 has secured to its free edge a batten 46 which serves as a stop against which the other door 39 is juxtaposed when the doors are in their relatively extended positions.

10 The doors when in their extended or operative positions (Figs. 2 and 4) are located over the outermost of the gutters 14 so that water splashed or otherwise delivered upon the doors will drain directly into the gutters. To facilitate the dripping of water from the doors the under side of each is made somewhat concave to afford dripping edges 47 such as shown in Fig. 4.

Medially of such edges there is provided 20 for each door a flexible swipe 48 of rubber, preferably, which functions to wipe moisture from the upper surfaces of the sink structure, and cover 26.

For taking a shower bath, the doors 38 25 and 39 are arranged as shown in Figs. 2 and 4, and the occupant may stand either in the sink or upon the cover 26, as desired.

For a foot bath one only of the doors 38 30 and 39 is advantageously used thereby enabling the bather to sit upon a chair or the like located outside of the compartment.

The waste pipe 16 is sufficiently large to readily carry off all water draining thereinto 35 from the sink 12 and the gutters 14. The location of the gutters with respect to the doors and the sink obviate all danger of flooding the room by an overflow or splashing of water.

The construction and operation of the invention in its preferred embodiment will be 40 understood from the foregoing description. Changes in the specific details of construction and arrangement of parts may be made within the scope of the appended claims 45 without departing from the spirit of the invention or sacrificing its advantages.

What I claim is,—

1. A foot-bath tub comprising a sink provided with a drainage opening, a stopper 50 for said opening, a sump communicating with said opening and having an outlet, a water supply for said sink, and a gutter surrounding the sink for carrying the overflow thereof into the sump.

55 2. A foot-bath tub comprising a sink provided with a drainage opening, a stopper for said opening, a sump communicating with said opening and having an outlet, a water

supply pipe extending into said sink, and a gutter surrounding the sink for carrying 60 the overflow thereof into the sump.

3. The combination with a shower sprinker, of a sink provided with a drainage opening, a removable apertured cover for the sink, said cover serving as a platform 65 for a bather, a sump having an outlet, and a gutter provided exteriorly of the sink for carrying waste water into said sump.

4. The combination with the walls and floor of a room, a sink provided in said floor, 70 a drainage opening for the sink, a sump communicating with said drainage opening and having an outlet, a gutter surrounding the sink for conveying waste water to the sump, a removable cover for the sink, an apertured cover for said gutter, the upper 75 surfaces of said cover being in a plane with the floor level, a pair of complementary doors hingedly connected to the respective walls and adapted to cooperate therewith to afford an enclosure for a bather above the sink, and means to supply water for bathing within said enclosure.

5. In apparatus as defined in claim 4, a grid provided for said gutters, flexible devices depending from the respective doors for obstructing the openings between the latter and the grid, said devices also serving as swipes for wiping moisture from the sink 80 cover when said devices are moved with the respective doors.

6. In apparatus of the character described, the combination with walls and floor of a room, of doors hingedly connected to the respective walls so as to be swung into 95 rectangular relations therewith to provide a bath cabinet within the room, a sink provided in the floor, a gutter surrounding the sink, the upper edges of the sink and gutter walls being in a plane with the upper surface of said floor, said gutters being arranged to receive dripping from the said doors.

7. In apparatus as defined in claim 4, grids provided for the gutters, a flexible 105 device depending centrally over the respective grids from each of the doors when the latter are in their relatively extended positions, whereby water is prevented from passing under the door onto the room floor.

Signed at Seattle, Washington, this 14th day of May, 1924.

EDWARD THOMAS OSBORN.

Witness:

PIERRE BARNES.
